BOX EJECTOR

Hale Paxton, Santa Ana, Calif., assignor, by
mesne assignments, to Food Machinery Corpora-
tion, a corporation of Delaware

Application September 30, 1935, Serial No. 42,750

8 Claims. (Cl. 1-10)

My invention relates to box lidding machines and more particularly to an ejector for discharging a box from such a machine after the lidding operation.

In the agricultural industry, fresh fruits and vegetables are packed in suitable crates or boxes for shipment to market. The packed containers are conveyed to a lidding machine such as that disclosed in the copending application of Hale Paxton et al., Serial No. 688,104, filed September 5, 1933, for Automatic lid nailing and strapping machine. After being lidded, the containers are discharged from the lidding machine onto a storage conveyor.

An object of my invention is to provide an ejector for a lidding machine that will automatically and quickly eject a box from the machine in response to the completion of a lidding operation.

Another object of my invention is to provide a mechanism that serves to position a box in a lidding machine in addition to ejecting the box after the lidding operation.

Still another object of my invention is to provide an ejector for a lidding machine having a vertically movable box supporting table in which the power for operating the ejector is derived in response to downward movement of the table.

Further objects and advantages will be made manifest in the following description taken in connection with the accompanying drawings, in which:

Fig. 1 is a front elevational view of a lidding machine which includes a preferred form of box ejector of my invention.

Fig. 2 is a fragmentary, side elevational view looking in the direction of the arrow 2 of Fig. 1.

Fig. 3 is a horizontal sectional view taken on the line 3-3 of Fig. 1.

Fig. 4 is a vertical sectional view taken on the line 4-4 of Fig. 3.

Fig. 5 is an enlarged, vertical sectional view taken on the line 5-5 of Fig. 4.

Fig. 6 is a fragmentary, vertical sectional view taken on the line 6-6 of Fig. 5.

Fig. 7 is a fragmentary, detail view of a portion of the mechanism shown in Fig. 4.

Fig. 8 is a vertical sectional view similar to Fig. 4 and illustrating position of the parts of the invention with a box being received into the machine.

Fig. 9 is a view similar to Fig. 8 showing the box as it first comes to rest in the machine with stops engaging both ends of the box.

Fig. 10 is a view similar to Fig. 9 illustrating the commencement of the ejection of a box from

the machine after the completion of a lid securing operation.

Fig. 11 is a fragmentary, side elevational view looking in the direction of the arrow 11 of Fig. 10.

Referring specifically to the drawings, a lidding machine 10, comprising a preferred embodiment of my invention, is shown in Fig. 1, this machine including a frame 11, power unit 12, box supporting table 13 and a lid securing mechanism which comprises two lid nailing units 14. With the exception of the table, 13, the machine 10 is substantially similar to the machine disclosed in the above referred to copending application.

The frame 11 includes a base 20 from which pairs of front and rear corner posts 22 and 23 respectively extend. Fixed on the upper ends of the posts 22 and 23 are front and rear plates 24 and 25 respectively. Secured at its opposite ends to the rear posts 23, as seen in Figs. 1 and 2 is a horizontal angle iron bar 26, the purpose of which will be made clear hereinafter. Mounted inside of each of the corner posts 22 and 23 is a track 27 having an inclined portion 28 at its lower end as seen in Fig. 2.

The power unit 12 includes a motor (not shown) for driving a gear 30, disposed within a housing 31 as shown in Fig. 1. A switch 32 is provided for controlling the motor in response to manual operation of a foot pedal 33.

The table 13 includes transverse bars 35 and 36, the ends of the latter being disposed in sliding relation with the corner posts 22 and 23 as shown in Fig. 3. Extending between the bars 35 and 36 are longitudinal bars 38, 39, 40 and 41, there being rollers 42 mounted between the bars 38 and 39 and the bars 40 and 41 as shown. Fixed on the under side of the table 13 and extending downward through the gear 30 is a screw 42.

Mounted on the table 13 (Fig. 2) are side flushers 45, these including horizontal shafts 46 journaled in the bars 35 and 36. Welded to opposite ends of the shafts 46 are levers 47 having rollers 48 on their upper ends, the rollers being disposed in vertical alignment with the aforementioned tracks 27 of the posts 22 and 23. Suspended between the lower ends of the levers 47 are springs 50, one of which is shown in Fig. 2. Extending upward from each of the flusher shafts 46 are arms 52 as shown in Fig. 1. Secured to the arms 52 of each of the flushers 45 is a bar 53 having arcuate end portions 54, the latter serving to centralize the box on the table 13 as shown in Fig. 11. Above the bar 53 on the outermost bars 52 are box end engaging arms 55 for centralizing a box longitudinally on the table 13 in a manner to be de-

scribed hereinafter. Mounted on the upper extremities of the arms 52 are side flusher plates 56.

Mounted between the bars 39 and 40 of the table 13 as shown in Fig. 3, is a bar 60, there being a short shaft 61 extending between the bar 60 and the bar 35. Rotatably mounted on the shaft 61 is a box stop 62 having an apertured ear 63 extending from one side thereof as shown in Fig. 2. The stop 62 is normally urged against the bar 60 by a compression spring 64 provided on the shaft 61. Connecting the ear 63 of the stop 62 with one of the levers 47 of the rear flusher shaft 46 is a contractable link 66, the latter being normally extended by a compression spring 67 as shown in Fig. 2.

Mounted on the table 13 is a box ejector 70 which includes a hollow shaft 71 journaled in a bearing 72 on the bar 38 as shown in Fig. 5. Fixed on one end of the shaft 71 is a pinion 73 positioned to mesh with a vertically disposed rack 74, the latter being fixed at its lower end to a block 75 on the angle iron bar 26 as shown in Fig. 5. Provided on the bar 38 of the table 13 adjacent the bearing 72 is a bracket 77 having a flanged roller 78 mounted thereon, the roller 78 serving to maintain the rack 74 in meshing relation with the pinion 73 as seen in Fig. 3.

Rotatably mounted in a bearing 80 on the bar 40 of the table 13 is a shaft 81, one end of which is rotatably received by the hollow end of the shaft 71 as shown in Figs. 5 and 10. Keyed on the shaft 81 is a sprocket 82 having a spring pressed pin 83 slidably mounted in the hub thereof. Rotatable on the shaft 81 between the sprocket 82 and the end of the hollow shaft 71 is a collar 85, the latter being formed to provide ratchet teeth 86 for engagement with the pin 83 of the sprocket 82. Coiled about the shaft 71 is a torsion spring 88 fixed at its ends to the shaft 71 and collar 85 as shown in Fig. 5. Fixed on the shaft 81 adjacent the bar 40 is a ratchet wheel 89 for engagement with a pawl 90 on the bar 40 as shown in Fig. 6. Surrounding the shaft 81 between the sprocket 82 and the ratchet wheel 89 is a spacer sleeve 91.

Provided between the bars 39 and 40 of the table 13 is a shaft 93 having a pair of spaced collars 94 fixed thereon, there being an idle sprocket 95 rotatable on the shaft 93 between the collars 94. Trained about the sprockets 82 and 95 is an endless chain 96. Pivotaly mounted on pins 97 of the chain 96 is a pair of identical box engaging dogs 98a and 98b, one of the latter being clearly shown in Fig. 7. Provided in side walls 99 of the dogs 98a and 98b are arcuate slots 100 for receiving the ends of pins 101 of the chain 96. The dogs 98a and 98b are normally urged outward from the chain 96 by spring fingers 102. Mounted on the aforementioned gear housing 31 is an angle bracket 104 for engagement with the dogs 98a and 98b as will be described hereinafter.

The nailing units 14 are constructed substantially as set forth in the above referred to co-pending application, and serve to secure a lid L shown in Fig. 1 to a packed box B.

Operation

The lidding machine 10 of my invention operates in the following manner. As the box B rolls onto the table 13 from a suitable delivery conveyor 110, the uppermost dog 98a is depressed as shown in Fig. 8, while the dog 98b engages the angle bracket 104 to prevent movement of the chain 96. When the box B strikes the stop 62,

as shown in Fig. 9, the stop 62 is moved leftward against the spring 64, thus permitting the dog 98a to return to its uppermost position. As the box B is stopped, the stop 62 urges the box into contact with the dog 98a as shown in Fig. 9, rightward movement of the dog 98a, as viewed in Fig. 9, being prevented by engagement of the pawl 90 with the aforescribed ratchet wheel 89.

When the box B is thus positioned between the stop 62 and dog 98a as shown in Fig. 9, the operator depresses the foot pedal 33 causing the power unit 12 to raise the table 13. As the table 13 rises, the flusher shafts 46 are rotated by engagement of the rollers 48 of the levers 47 with the tracks 27 causing the flushers 45 to swing inward against the box B as shown in Fig. 11, it being noted that the ends 54 of the bars 53 are pressed against the sides of the box while the arms 55 engage the ends of the box. Rotation of the rear flusher shaft 46 also causes link 66 to rotate the stop 62 out from in front of the box end as shown in Figs. 10 and 11, it being noted that as soon as the stop 62 clears the box end, the spring 64 urges the stop partially under the box against the bar 60. During upward travel 25 of the table 13, the shaft 71 is rotated by engagement of the pinion 73 with the rack 74. The spring 88 and collar 85 are rotated with the shaft 71 while the shaft 81 remains stationary, reverse rotation thereof being prevented by engagement 30 of the pawl 90 with the ratchet wheel 89. As the table 13 rises to its uppermost position, the lid L is pressed onto the contents of the box and nailed at its ends to the ends of the box. When the table 13 moves downward following the 35 lid nailing operation, the shaft 71 is again rotated by the rack 74, but in the opposite direction to that during upward movement of the table 13. The torsion spring 88 rotates with the shaft 71 but the collar 85 is locked by engagement of one 40 of the teeth 86 thereof with the pin 83 of the sprocket 82. Thus, as the table 13 descends, power is stored in the spring 88 as the latter is wound up, this power tending to rotate the sprocket 82 in a counter clockwise direction as 45 viewed in Fig. 10. The dog 98a is thus urged against the rear end of the box B while the latter is prevented from moving on the table 13 by the arms 55 of the flushers 45.

As the table 13 approaches its lowermost position, the rollers 48 of the levers 47, roll down the inclined portions 28 of the tracks 27 causing the flushers 45 to swing outward away from the box B. As the arms 55 move out from in front of the box B, the sprocket 82 is rotated by the 55 unwinding of the spring 88, causing the dog 98a to urge the box B off of the table 13 onto a suitable conveyor 112. While the box B is being discharged from the machine 10 by the ejector 70, the table 13 arrives at its lowermost position and 60 the chain 96 is stopped after ejecting the box by engagement of the dog 98a with the angle bracket 104, the dog 98b being disposed in the position of the dog 98a shown in Fig. 4.

That portion of the entire operation of the 65 machine 10 which is directly involved in the securing of the lid L onto the box B and which may be termed a lid securing operation of the machine, begins with the contact of the box being elevated on the nailing table 13 with the lid 70 securing mechanism disposed thereabove and terminates with the downward movement of this box as it passes out of contact with said mechanism.

Although I have shown and described but one 75

preferred form of my invention, it is to be understood that various modifications and changes might be made therein without departing from the spirit of the invention or the scope of the following claims.

I claim as my invention:

1. In a machine for securing a lid on a packed box, the combination of: a supporting structure; a table on said structure for receiving and supporting a box; lid securing mechanism on said structure above said table; power means causing relative vertical movement between said table and said lid securing mechanism to effect a lid securing operation and causing a second relative vertical movement between said table and said lid securing mechanism to restore the normal vertical spaced relationship between said table and said mechanism; a primary stop on said table to engage the front end of said box; a secondary stop on said table to engage the rear end of said box, said primary and secondary stops cooperating to center said box longitudinally on said table; means for removing said primary stop from in front of said box; and means for moving said secondary stop toward said primary stop to eject said box from said table subsequent to said lid securing operation.

2. A combination as in claim 1 in which said means for moving said secondary stop toward said primary stop is actuated in response to said second relative vertical movement between said table and said lid securing mechanism.

3. In a machine for securing a lid on a packed box, the combination of: a frame; lid securing mechanism on the upper end of said frame; a box supporting table on said frame below said lid securing mechanism, said table being movable vertically toward and away from said lid securing mechanism; a primary stop on said table for engaging the front end of said box; a secondary stop on said table for engaging the rear end of said box, said primary and secondary stops serving to centralize said box longitudinally on said table; means for removing said primary stop from in front of said box; and means for moving said secondary stop toward said primary stop to eject said box from said table, said last mentioned means being actuated in response to downward movement of said table following a lid securing operation.

4. In a machine for securing a lid on a packed box, the combination of: a supporting structure; a table on said structure for receiving and supporting a packed box; lid securing mechanism on said structure above said table; power means causing relative vertical movement between said table and said lid securing mechanism to effect a lid securing operation and causing a second relative vertical movement between said table and said lid securing mechanism to restore the normal vertical spaced relationship between said table and said mechanism; an endless chain extending longitudinally relative to said table; means on said chain for engaging an end of said

box; and power means for setting said chain in motion after a lid securing operation to cause said box engaging means to quickly expel said box from said table.

5. A combination as in claim 4 in which said chain is actuated in response to said second relative vertical movement between said table and said lid securing mechanism.

6. In a machine for securing a lid on a packed box, the combination of: a frame; lid securing mechanism on the upper end of said frame; a box supporting table on said frame below said lid securing mechanism, said table being movable vertically toward and away from said lid securing mechanism; an endless chain extending longitudinally relative to said table; means on said chain for engaging an end of said box; and means responsive to downward movement of said table for setting in motion said endless chain to cause said box engaging means to expel said box from said table.

7. In a machine for securing a lid on a packed box, the combination of: a supporting structure; a table on said structure for receiving and supporting a box; lid securing mechanism on said structure above said table; means causing relative vertical movement between said table and said lid securing mechanism to effect a lid securing operation and causing a second relative vertical movement between said table and said lid securing mechanism to restore the normal vertical spaced relationship between said table and said mechanism; means for retaining said box in centralized relation to said table during said lid securing operation and releasing said box thereafter; endless chain means on said table; a box engaging dog on said chain; and power means yieldably connected to said chain to urge said dog against said box in response to said second relative vertical movement and eject said box from said machine.

8. In a machine for securing a lid on a packed box, the combination of: a supporting structure; a table on said structure for receiving and supporting a box; lid securing mechanism on said structure above said table; power means causing relative vertical movement between said table and said lid securing mechanism to effect a lid securing operation and causing a second relative vertical movement between said table and said lid securing mechanism to restore the normal vertical spaced relationship between said table and said mechanism; means for retaining said box in longitudinally centralized relation to said table during said lid securing operation; endless chain means on said table; a box engaging dog on said chain means; rack and pinion means operable in response to said second relative vertical movement; and spring means connecting said rack and pinion means and said chain to yieldably transmit power from said rack and pinion means to said chain.

HALE PAXTON.
